UNITED STATES PATENT OFFICE.

JOHAN HUEBNER, OF HAMMOND, INDIANA, ASSIGNOR TO HANS KRAUT MANUFACTURING COMPANY, OF CHICAGO, ILLINOIS.

WASHING-MACHINE.

No. 889,930.

Specification of Letters Patent.

Patented June 9, 1908.

Application filed June 14, 1907. Serial No. 379,012.

To all whom it may concern:

Be it known that I, JOHAN HUEBNER, citizen of the United States, residing at Hammond, in the county of Lake and State of Indiana, have invented certain new and useful Improvements in Washing-Machines, of which the following is a specification.

This invention is a washing machine of the oscillating type which operates with or is operated by a rocking chair in which the operator sits and rocks back and forth to effect the desired result.

The invention is illustrated in the accompanying drawings, in which

15 Figure 1 is a front elevation of the machine. Fig. 2 is a side elevation with the tub in section. Fig. 3 is a top plan view of the machine, with the cover partly broken away. Fig. 4 is a side elevation of the presser used in 20 the machine. Fig. 5 is a side elevation of a modified form of presser. Fig. 6 is a detail in section.

Referring specifically to the drawings, 1 indicates a chair and 3 the tub of the washing 25 machine. These are mounted upon rockers 2 which set in a bed frame 4. At one end of the frame is a standard 5 which overhangs the tub and has fixed thereto a depending bar 6 on which is fulcrumed a rocking or 30 working lever 7 to the opposite ends of which are pivoted connecting rods 8. The rods 8 are connected to corrugated and perforated bed plates 10, upon which the clothes are placed. These plates are hinged together at 35 the middle, and rest upon a double inclined wooden base or platform 11 which is mounted and supported upon spiral springs 12 resting on the bottom of the tub.

A presser is indicated at 9, consisting of a 40 frame extending crosswise between the sides of the tub and above the bed 10. The end pieces of the presser have lugs 9^b which fit in vertical grooves formed by spaced strips 9^c secured to the opposite sides of the tub. At 45 the top the presser is connected by a cross rod 13 to the lower end of the vertical bar 6 which, as said, is fastened to the overhanging standard 5.

Spiral springs 15 are connected from the 50 frame 4 to the rocker, both front and rear, and serve to prevent the tub from rocking too

far either forward or backward, and the springs help the operation when it is started.

18 is a spring which extends from one end of the base frame 4 to the other, above the 55 rockers, and its object is to hold the rockers to or upon the frame 4, preventing jumping or excessive movement while allowing the necessary movement to effect the object of the device. If it were not for the spring 18 the 60 rocking movement would or might cause the rocking structure to shift or slide in the bed frame. This spring simply tends to prevent such shift and to hold the parts in place.

The tub has a cover 19 formed in two parts 65 with a slot 19^a therebetween, through which the rods 8 operate.

In the operation of the machine, a person sitting in the chair and rocking will cause the tub to oscillate, as indicated in dotted lines 70 in Fig. 1, the result of which will be that one rod 8 will move upward and one move downward, acting on the lever 7, and drawing one end of the bed 10 upwardly and pressing the other end of said bed downwardly, and at 75 the same time the lower end of the presser 9 swings. Said presser is inclined or leaned toward the side of the bed 10 which is being lifted, and clothes located between the presser and that side of the bed are pressed or 80 squeezed, and the dirt dislodged therefrom. When the chair is rocked back, the operation is reversed, or repeated in the other end of the tub. The perforations in the bed 10 allow the water to be forced up through the 85 same, and through the clothes at each oscillation, and the water will flow or be forced from one end of the tub to the other, passing through clothes as they are being pressed and effectively dislodging the dirt therefrom. 90 For ordinary clothes the presser having the projections 9^b may be used, but for fine fabrics the presser shown in Fig. 5 will be preferable, having simple slats 9^d extending across the same, to press upon the fabrics 95 or articles in the tub.

I claim:

1. The combination of an oscillating tub having a flat bottom, a presser extending across the tub at the middle thereof and having a hinge connection at the top to an exterior support and a pivotal connection at the

bottom to the sides of the tub, a bed located in the tub and extending at an inclination downwardly from each end thereof toward the pivot of the presser, and supporting 5 springs under the bed, at each end thereof.

2. The combination of an oscillating tub, a presser supported in the middle thereof, a lever exteriorly-supported above the tub, a bed connected at its opposite ends to the

ends of the lever and arranged to rock within 10 and relative to the tub toward and from the presser.

In testimony whereof I affix my signature, in presence of two witnesses.

JOHAN HUEBNER.
